UNITED STATES PATENT OFFICE.

EDWIN M. PARKER, OF BRIDGEPORT, CONNECTICUT, ASSIGNOR TO PARKER & DAVIS, OF SAME PLACE.

DESIGN FOR A SPOON, &c.

SPECIFICATION forming part of Design No. 20,914, dated July 7, 1891.

Application filed May 12, 1891. Serial No. 392,511. Term of patent 7 years.

To all whom it may concern:

Be it known that I, EDWIN M. PARKER, a citizen of the United States, residing at Bridgeport, in the county of Fairfield and State of Connecticut, have invented and produced a new and original Design for Spoons, Forks, and Similar Articles; and I do declare the following to be a full, clear, and exact description of the same, reference being had to the accompanying photographic illustration, forming a part thereof.

The leading feature of my design consists in the original ornamentation on the handle.

The figure is an elevation illustrating my design applied to the handle of a spoon.

a denotes the bust of a man upon the broadened portion of the handle, which is a likeness or conventional representation of P. T. Barnum.

b denotes a panel, upon which a suitable inscription may be placed.

c denotes conventional ornamental work on the face of the tip of the handle, and *d* denotes conventional ornamental work on the broadened portion of the handle between the bust and the panel.

What I claim is—

The design for handles for spoons, forks, and similar articles, substantially as shown and described.

In testimony whereof I affix my signature in presence of two witnesses.

EDWIN M. PARKER.
